UNITED STATES PATENT OFFICE.

GEORGE C. VIDETTO, OF PITTSBURGH, PENNSYLVANIA.

CONVEYING APPARATUS.

1,426,691.

Specification of Letters Patent. Patented Aug. 22, 1922.

Application filed July 3, 1920. Serial No. 393,909.

To all whom it may concern:

Be it known that I, GEORGE C. VIDETTO, a citizen of the United States, residing at Pittsburgh, in the county of Allegheny and State of Pennsylvania, have invented certain new and useful Improvement in Conveying Apparatus, of which the following is a specification.

My invention relates to improvements in a loading apparatus for loose material, such as coal, gravel, sand, etc., and has for its object to provide a machine capable of being used in various locations to remove the material from its position in bulk and to deliver it to any desired subsequent point or location, as into cars or the like.

Generally stated, the apparatus comprises a portable truck having a receiving conveyor, adapted to be set at various angles or degrees of incline and to discharge the load from its outer end, and a loading drum so connected with the conveyor truck and with relation to the conveyor as to remove the material from its position in the pile or bank to the conveyor, together with suitable driving mechanism and various other features of construction and operation, as shall be more fully hereinafter described.

Referring to the drawings, illustrating one preferred embodiment of the invention,

Fig. 1 is a view in side elevation of the entire apparatus in position for operation;

Fig. 2 is a plan view of Fig. 1;

Fig. 3 is a view in elevation from the inner end; and

Fig. 4 is a transverse sectional view on the line IV—IV of Fig. 1.

The main framework of the apparatus, comprising the supporting truck for the conveyor, is built of suitable structural material having the main side beam members 2—2 of channel or other suitable shape, with end framing 3. The main truck is supported upon a pair of driven wheels 4—4 and front dirigible wheels 5—5. The rear portion of the machine, comprising the removing wheel portion, is carried by a supplemental supporting frame 6 composed of two side bars similar to bars 2, and each is pivoted by cross shaft 7 in the brackets 8 and 9 respectively of the two main frames. The purpose of such mounting is that the rear framework carrying the removing drum may be adjusted vertically with rela-

tion to the main conveyor frame, to adapt it to inequalities in the ground surface, the pile of material being acted upon, or other conditions.

Extending upwardly and rearwardly from the main frame 2 are the posts 10—10 connected by stay rods 11 to the main side bars 2 and provided with a transverse shaft 12 and sheaves 13 thereon for the lifting cables 14. Said cables are connected at each side of the supplemental frame 6, as at 15, 60 pass upwardly over sheaves 13, and then downwardly and around the winding drum 16 of shaft 17, having the ratchet controlled winding gearing 18 of well known construction, whereby the drum frame may be raised 70 and held at any desired position or elevation, or may be lowered below the normal horizontal level, as required.

The digging or removing drum or wheel, which is the initial active element of the apparatus, is mounted upon a transverse shaft 19 in the rear end portion of frame 6, and is constructed of sheet metal, or otherwise, to provide a continuous series of buckets or pockets 20 with intervening scooping edges 21, adapted to be rotated in the direction of the arrow to lift segregated portions of the loose material to deposit it upon the inner end of the conveyor A. The scooping edge 21 and buckets 20 extend transversely of the drum between outer sides 22 of sheet metal or cast steel, whereby to provide closed end pockets similar to the usual pockets of an ordinary bucket conveyor.

The edges 21 may be merely continuous 90 terminals of the metal of the buckets, as in operation on ordinary loose material, as sand, etc., but where it is desirable to operate upon coarser material, as heavy gravel, lump coal, or similar material, I prefer to 95 provide at one or more locations around the periphery of the drum, as for instance, along each alternate edge of the bucket series, a series of projecting teeth or points 23 secured by their inner terminals 24 to the 100 edge of the sheet metal, as will be readily understood. In such case, the teeth will operate to cut through coarser material, segregating and loosening it, rendering it possible for the plain edge buckets to scoop 105 and elevate it and carry it around for deposit upon the receiving end of the conveyor A.

Said conveyor may be of any suitable construction, as a belt 25 passing around an inner driving drum 26 and an outer drum 27 mounted in adjustable journal boxes 28, carried in framework 29 of the conveyor, the inner end of which is pivotally mounted on transverse shaft 7, and capable of vertical adjustment. Conveyor belt 25 is supported in any suitable way, as by a series of upper and lower transverse rollers 30-31 of well known construction.

Lifting post 32, bearing upon the under side of the conveyor frame by one or more rollers, is mounted upon the end framing 15 portion of the main truck 2 having the guiding housing 34 and a lifting cable 35 engaging a terminal sheave 36, and provided with a winding drum 37 and suitable ratchet controlled gearing 38, whereby the 20 elevator A may be located at any desired inclination for delivery from its outer end.

Ordinarily, the conveyor A and the removing drum, generally designated by the letter B, are operated together, by means 25 of sprocket gearing 39 and 40, utilizing the usual sprocket chains and wheels, whereby to transmit movement from the shaft 41 thereto. Said shaft 41 is driven by sprocket gearing 42 utilizing the usual chains and 30 wheels, from shaft 43, which is driven through gearing 44 from a motor or other prime mover 45.

Clutch mechanism 46, operated by levers 47 and 48, is adapted to transmit driving 35 motion in the desired direction to traction wheels 4 through gearing 49 and 50 of each traction wheel, whereby to propel the apparatus forwardly or backwardly. A clutch 51 between the oppositely driven bevel 40 gears 52-52 of shaft 43 and operated by lever 53, provides for reversing the direction of shaft 41, it being understood that clutch 46 may be thrown out of gear at any time, as for instance, when the digging 45 and scoop loading drum B would otherwise be operated in an undesired reverse direction.

By the gearing above described, it will be understood that traction may be imparted to the main truck wheels 4 for transportation of the apparatus, in which case the removing drum may be elevated away from contact by its lifting mechanism 14, etc., and that when located in position for 55 operation with the removing or loading drum lowered, the traction gearing is inactive, the power of the motor being then utilized to drive the conveyor and removing drum together.

It will, of course, be understood that a 60 gas engine or other prime mover may be substituted for the electric motor 45 shown in the drawings and that the invention is in no way restricted to the particular kind 65 of motor utilized. Guiding mechanism for

wheels 5 of any suitable kind may be used, as knuckles 54 connected with a cross rod 55 actuated by lever 56 and gearing 57 provided with a hand wheel 58 generally similar to that utilized in clutch mechanism.

70

The construction and operation of the invention will be readily understood and appreciated from the foregoing description. Mounted upon the main supporting frame as it is, the machine may be transported under its own power over any suitable surface, and located in position to operate upon a pile of loose material C, as for instance, sand, coal, or the like. Drum B having been adjusted and conveyor A raised to 75 the desired inclination, as for instance, sufficiently high to deliver into a receiving wagon, mine car, or the like, gearing 39, 40 and 42 will transmit driving movement simultaneously to the drum and conveyor, 80 so that the drum, in its rotation, will scoop up segregated quantities of the loose material of the pile and will deliver them on to the receiving end of the conveyor, which will then carry the material outwardly in 85 the usual way, and deliver it over the terminal drum 27 by gravity.

90

The apparatus is very compact, comparatively simple in construction and operation, light and portable, and inexpensive to build 95 and maintain. It is capable of being used in many locations where it can be substituted for manual handling of the loose material, as in quarries, mines, or elsewhere, and is well adapted to perform its intended 100 functions in a highly satisfactory manner.

The invention may be variously changed or modified by the skilled mechanic in various details or otherwise, but all such changes are to be considered as within the 105 scope of the following claims.

What I claim is:

1. A loading and conveying apparatus comprising a supporting truck, a conveyor pivotally mounted thereon, means for raising and lowering the conveyor, a rotatable loading drum arranged to scoop up material and empty it onto the conveyor, a frame therefor pivotally connected with the conveyor truck, means whereby the frame may be raised and lowered independently of the conveyor into such positions that its gathering portion may be below or above the terminal of the conveyor, and operating mechanism for the conveyor and loading drum.

2. A loading and conveying apparatus comprising a supporting truck, a conveyor pivotally mounted thereon at its receiving end and, means for raising and lowering one end of the conveyor about the pivot, a rotatable loading drum arranged to scoop up material and empty it onto the conveyor, a frame for supporting the drum pivotally connected with the truck, the axis of the

pivot for the drum supporting frame and of the conveyor being common, and means for driving the conveyor and loading drum.

3. A loading machine comprising a supporting structure, a conveyor pivotally mounted thereon, at its receiving end and means whereby the conveyor may be raised and lowered, a rotating loading drum arranged to scoop up material and empty it in the receiving end of the conveyor, the axis of rotation of the drum being disposed in advance of the receiving end of the conveyor, a frame in which the drum is carried pivotally connected with the supporting structure, and means whereby the drum supporting frame may be maintained at different angles relatively to the conveyor.

4. A loading machine comprising a supporting structure, an inclined endless conveyor supporting frame having a roller supporting shaft at each end thereof, the shaft at the lower end serving to pivotally support the conveyor frame in the supporting structure, an endless conveyor carried by the conveyor frame, a loading drum carrying frame extending in advance of the supporting frame, said drum carrying frame being pivotally supported about said lowermost shaft, a loading drum rotatably mounted in the drum supporting frame and arranged to scoop up material and deliver it onto the lowermost end of the conveyor, means for driving said lowermost shaft, and means for operatively connecting the drum and shaft.

5. A loading machine comprising a supporting structure which includes a pair of spaced apart side frame members having depending portions at their forward ends, wheels on which the supporting structure is carried, a shaft extending across the side frame members and journalled in the depending portions, an inclined conveyor frame having one end thereof pivoted about said shaft, means whereby the frame may be raised and lowered, a conveyor in the conveyor frame, the lower end of said conveyor extending below the level of the side frame members, a loading drum carrying frame comprising side frame members having depending portions thereon journalled about said shaft, a loading drum having buckets in its periphery arranged to scoop up material and empty it onto the conveyor carried in the drum carrying frame, means on the shaft for driving the conveyor and loading drum, and means whereby the drum carrying frame may be inclined at different angles relatively to the conveyor.

6. The combination with a loading conveyor, of a drum disposed at the receiving end thereof, said drum having its periphery provided with a series of adjacent transversely extending pockets having outer edges for scooping up the material, some

of the edges thereof being provided with prongs while the edges of others are substantially smooth, the pronged edges being terminated substantially the same distance from the center of the drum as the smooth edges.

7. The combination with a loading conveyor, of a drum disposed at the receiving end thereof, which drum is provided with a series of transversely extending pockets, the edges of which are alternately smooth and pronged, all of said edges terminating substantially the same distance from the center of the drum.

8. The combination with a loading conveyor, of a drum disposed at the receiving end thereof, which drum comprises spaced apart annular end plates having a structure therebetween which forms a series of transversely extending fixed pockets, the edges of said pockets terminating substantially flush with the periphery of the annular end plates.

9. A loading machine comprising a supporting frame, a conveyor carried therein, a loading drum rotatably carried in the frame and arranged to scoop up material and deliver it onto the conveyor, said drum having a plurality of buckets therein, with one side of the bucket arranged to gather material and the other side arranged to provide an inclined face over which material scooped up by the gathering face falls onto the conveyor, the gathering edge of one of the buckets being set in from the periphery, it being terminated on a radius shorter than the radius of other buckets of the series, and teeth on the said edge extending out to the periphery of the drum.

10. A loading machine comprising a supporting frame, a conveyor carried therein, a loading drum rotatably carried in the frame and arranged to scoop up material and deliver it onto the conveyor, said drum having a plurality of buckets therein with one side of the bucket arranged to gather material and the other side arranged to provide an inclined face over which material scooped up by the gathering face falls onto the conveyor, the gathering edges of alternate buckets being set in from the periphery of the drum and terminating on a radius shorter than the radius in which the other gathering edges terminate, and teeth on the said set-in edges which extend out to the periphery of the drum.

11. A loading machine comprising a supporting frame, a conveyor carried therein, a loading drum rotatably carried in the frame and arranged to scoop up material and deliver it onto the conveyor, said drum comprising a pair of spaced apart end plates between which is secured a continuous series of adjacent buckets arranged to gather up material and deliver it into the

conveyor, said buckets having gathering edges, the gathering edges on some of the buckets being set in from the periphery of the drum while the gathering edges of the 5 other buckets terminate at the periphery, and teeth on said set-in edges which extend to the periphery of the drum.

12. A loading machine having a loading drum therein, said drum having an annular 10 series of buckets therein, said buckets hav-

ing gathering edges, the gathering edges of some of the buckets extending to the periphery of the drum while the gathering edges of other of the buckets are set in from the periphery, and teeth on the set-in edges 15 extending out to and terminating at the periphery of the drum.

In testimony whereof I hereunto affix my signature.

GEORGE C. VIDETTO.
